UNITED STATES PATENT OFFICE

EDWARD A. REESE, OF MILWAUKEE, WISCONSIN

FURNACE-WALL CONSTRUCTION

Application filed November 18, 1929. Serial No. 408,052.

This invention relates to new and useful improvements in furnace wall construction.

One of the objects of my invention is the provision of an improved construction in furnace walls adapted for steam boiler furnaces, wherein the wall is especially constructed for pre-heating the air supplied to the combustion chamber in the furnace and at the same time prevent the heat from damaging the wall, while the outer portion of the wall is especially constructed so that the same can be cooled by currents of air passing through the wall.

Another object of the present invention is the provision of an improved construction in furnace and similar walls, which will provide for the removal and repair of certain sections of the wall without interfering with adjoining sections so that any of the refractory units can be readily removed and easily replaced.

A still further object of the invention is the provision of furnace wall construction wherein the inner wall portion is built up in units with appropriate supporting elements for the units whereby any one of the units can be removed for repairs or replacement and the outer wall is maintained in spaced relation with the inner wall by a plurality of I-beams, the outer wall being of such construction that it will be readily cooled by the air passing through the two walls.

With the above and other objects in view, the invention consists in the novel features of construction, the combination and arrangement of parts hereinafter more fully set forth, pointed out in the claims and shown in the accompanying drawings wherein:

Figure 1 is a sectional view through one side of the wall with an adjacent side wall in elevation;

Figure 2 is a horizontal section looking in plan view upon a portion of one of the units with the end parts thereof broken away.

In a great many furnaces in use at the present time, the fuel used is coal of very fine particles which is known as mine shavings, and is rather difficult to feed this type of fuel to a furnace and produce the proper combustion due to the dampness of the material,

and it is, therefore, one of the principal objects of my invention to provide a furnace wall construction whereby the air is heated within the walls and used for blowing this fine fuel into the furnace, the blowing of the fuel into the furnace under draft will have a tendency to dry it to a certain extent before it reaches the combustion chamber.

In the construction of furnaces at the present time, it is somewhat difficult to remove deteriorated parts, and it is, therefore, another object of this improved construction to so construct the walls so that a portion of the walls could be removed for repairs when desired.

The wall structure is preferably laid upon a cement base 1, and positioned in opposed parallel relation upon the base 1 are the U-beams 2. These U-beams 2 are properly positioned according to the size and shape of the wall to be built on the cement base and are bolted together at their upper edges by means of the angular plates 3. These plates 3 have their horizontal portions extending across upon one side of the U-beams 2 with a securing bolt 4 passing through one of the side flanges of each U-beam and through the plates as is clearly illustrated in Figure 1.

Resting upon the upper edges of the U-beams 2 are the vertically disposed I-beams 5 held in position upon the U-beams by means of the vertically disposed sides of the plates 3 with fastening bolts 6 extending through the plates 3 and through the intermediate portion of the I-beams.

The U-beams 2 and the I-beams 5 form the general frame work of my improved wall and divide the entire wall structure into inner and outer sections so as to leave an air space between the two wall sections. The wall sections forming the sides, back and front of the furnace are built of a plurality of fire brick 7 with each wall section resting upon U-plates 8, the inner side walls of which are bolted to the outermost U-beam 2, as shown in Figure 1.

Upon the outer surface of each outer wall section is a layer of insulating asbestos 8 and arranged over the exterior of the asbestos

lining is a steel housing 9. The lower edge of this steel housing 9 is bolted to the outer side wall of the U-plate 8 by means of the screw bolts 10.

5 In the construction of each outer wall section, it is advisable to insert at different heights in this structure, additional U-plates 8' which are also secured in position by having their inner side walls attached to the 10 I-beams and their outer side walls attached to the steel housing 9.

15 In constructing the inner wall sections, it is first advisable to build up a lower section generally indicated at 11 by means of ordinary fire-brick. In the present instance, I have illustrated the lower section 11 comprising six layers of fire brick and upon top of this section 11 is laid a plurality of comparatively large tile indicated at 12. The 20 sides and ends of the tile 12 which are laid upon the upper edge of the section 11 extends beyond the upper layer of fire brick and rest upon angle plates 13 which are bolted to one of the cross flanges of the I-beams, as shown in Figure 1. In order to 25 provide for the expansion of the sides and ends of the larger tile 12, suitable angular notches 15 are cut into the tile to receive the inner cross portions of the I-beams and these notches are cut sufficiently large to provide 30 for the contraction and expansion of the tile when heated.

35 Upon the first layer of tile 12 is a second section of fire brick indicated at 16, this section being built up the same as the first section 11, and upon top of this section is another layer of comparatively larger tile 12' which are supported upon the angular brackets 13' attached to the inner cross portions 40 of the I-beams.

45 The wall may be built as high as desirable following the outline as described above with either a layer of large tile at the top of the wall or fire brick, and it will be apparent that by positioning the comparatively large tile 12 and supporting them upon the angular brackets 13 and 13', the section of fire 50 brick arranged beneath each layer of tiling can be easily removed without interfering with a section on either side thereof.

55 It will also be noted that at the ends of the U-beams 2, there is a suitable opening for the reception of air from the outside of the furnace wall which will pass inwardly and circulate outwardly and around through the furnace wall between the inner and outer sections, and if found desirable can be drawn off from the top of the wall or any other suitable location to be used for feeding the 60 comparatively fine fuel to the furnace. The housing 9 can be traced and connected at the corners by means of the angular plates 17, the sides of which are bolted to the adjacent sections of the steel housing 9, as shown 65 in Figure 2.

Attention is also directed to the fact that at each corner of the furnace, the tile section does not extend out over the passageways between the I-beams, but extends out sufficiently so that the tile are properly supported upon the angular plates 13 and 13', but leaves considerable space at the corners for the circulation of the air between the two wall sections. 70

75 It will be apparent from the foregoing that by constructing a furnace in the above manner, the inner wall section will stand a high degree of heat due to the cooling space upon the exterior thereof and, regardless of the heat developed within the inner wall sections, the outer steel housing 9 will remain in a comparatively cool state due not only to the cooling space between the inner and outer wall sections, but also due to the lining 8 of asbestos or other similar insulating material, 80 thus a high degree of heat may be maintained in the furnace but still allow the outside of the steel housing to remain in a comparatively cool condition.

85 It will also be noted that in constructing 90 a furnace along the above lines, a considerable quantity of pre-heated air can be utilized for drying fine coal fuel as it is fed into the furnace so as to improve the combustion of this type of fuel. 95

100 It will also be noted that any one of the fire-brick sections or any parts thereof can be quickly and easily removed for repairing without disturbing any of the other sections. It will also be noted that this type of furnace wall construction can be put up at a comparatively low cost when taking into consideration the efficiency of such a structure.

105 While I have shown and described the preferred embodiment of my invention, it will be apparent that slight changes may be made in the construction when putting the invention into practice without departing from the spirit of the same or the scope of the appended claims. 110

I claim:

115 1. In a wall construction, spaced inner and outer wall sections, a base member at the bottom of the wall sections and arranged between the same, vertically disposed I-beams resting upon the base member and spacing the walls, angular brackets carried by the I-beams and arranged in spaced relation, the inner wall section being formed in units with the lower layer of each unit engaged with the angular brackets on the I-beams, whereby any one of the units may be displaced without displacing the other units, and means providing for the contraction and expansion of the units under high temperature. 120 125

2. In a wall construction, spaced inner and outer wall sections, I-beams arranged between said wall sections, the inner wall section being formed in units with the lower layer of each unit formed with angular 130

notches to loosely receive the inner cross portions of the I-beams to provide for the expansion and contraction of the members provided with said notches.

5 3. In a wall construction, spaced inner and outer wall sections, a steel housing enclosing the outer wall section, I-beams arranged between said wall sections, U-shaped members positioned in spaced relation in the outer wall
10 section and having their side portions connected to the steel housing and to one side of the I-beams.

15 In testimony that I claim the foregoing I have hereunto set my hand at Milwaukee, in the county of Milwaukee and State of Wisconsin.

EDWARD A. REESE.
